Jas. H. Conklin, Peekskill N. Y. Letters Patent
No 196. dated Aug 22nd 1848. (Assigned to Whitney & Montanya)

The Schedule referred to in these Letters Patent and
making part of the same

To all whom it may concern: Be it known that I,
James H. Conklin, of the village of Peekskill in the County
of Westchester, and state of New York, have invented a new
Design for a Radiator stove which is described as follows, re-
ference being had to the annexed drawings of the same ma-
king part of this specification.

Figure 1 is a plan of the top plate cast thin as a curvi-
linear or dome like and ornamented with foliated and curved
enrichments as represented; it is lettered "Whitney & Montanya"

Figure 2, is a plan of the bottom plate also cast of a curved convexo-concave form received in the center, and perforated; but not dome-shaped, with circular apertures surrounded by conducting tubes & ornamented with fringed ornaments such as are represented in the annexed drawings, which are also represented at letters c "Design Patented 1848 - Whitney and Montanya".

Figure 3 is one of the plates that forms one of the sides of the base.

Figure 4 is a birds eye view of the plate that forms the top of the base.

Figure 5 is a view of one of the legs of the stove secured by rivets or screws to the under side of the bottom plate. The three legs are all made and ornamented alike.

The bottom plate is made in its general form convex - the central portion A however, is received for the reception of the base of the fire chamber and air tubes &c. and its convex surface is enriched and ornamented around the border according to the figures represented at B in figure 2.

The design of the top plate consists of three sections of domes each ornamented on its external surface the central dome C being larger than the two side domes D.D.

Figure 6 is a vertical longitudinal section on the dotted line x x of figure 1.

Figure 7 is a vertical longitudinal section on the dotted line o o of figure 2.

Figure 8 is a vertical section on the dotted line z z of figure 4.

Similar letters in the several Figures refer to corresponding parts.

What I claim as my invention and desire to secure by Letters Patent is the above described Design for a radiator stove

Dec. 196

which is fully set forth in the drawings accompanying this description.
